UNITED STATES PATENT OFFICE.

LOUIS MAURICE BARMAN, OF HOLBORN, LONDON, ENGLAND, ASSIGNOR TO RONEO LIMITED, OF LONDON, ENGLAND, A COMPANY OF GREAT BRITAIN.

ADDRESSING MACHINE OR LIKE PRINTING MACHINE.

Application filed August 21, 1922. Serial No. 583,421.

To all whom it may concern:

Be it known that I, LOUIS MAURICE BARMAN, a citizen of the United States of America, residing at Roneo Building, 5 Holborn, London, E. C. 1, England, Great Britain, have invented new and useful Improvements in Addressing Machines or like Printing Machines, of which the following is a specification.

- 10 This invention relates to improvements in addressing machines or like printing machines of the type wherein stencil cards are employed, and has for its object to provide means whereby contact of the presser roller 15 with the inking roller may be interrupted at the will of the operator.

In addressing machines of the type referred to, a stack of stencil cards are placed in a hopper and are withdrawn therefrom, 20 one at a time for printing the addresses on envelopes, wrappers, labels or the like when acted upon by the presser roller and the inking roller.

With such machines it sometimes happens 25 that certain cards placed in the hopper are not required to be used, and it would be advantageous to provide means whereby a skipping arrangement can be operated when a card or cards bearing some identification 30 mark is automatically withdrawn from the pile for printing.

The way and manner in which the invention is carried out will be understood by reference to the accompanying drawings 35 whereon.

Fig. 1 is a diagrammatic view of a type of addressing machine with which the invention is incorporated.

Fig. 2 is a plan view of the mechanism 40 for effecting the skipping arrangement.

Fig. 3 is a diagrammatic side view of the device.

Referring to Fig. 1, the hopper A containing the stencil cards B is secured upon a fixed track or slideway C within which works a reciprocating pusher member D which acts upon the lowermost stencil card and pushes it along the slideway to a position between a mutilated or segmented inking roller E 45 and a similarly mutilated or segmented presser roller F (Figs. 2 and 3). The inking roller E receives its ink from a set of rollers G carried by or supported between arms or brackets H attached to one side wall of the 50 hopper A, one of the said rollers G con-

tacting, when desired, with the ink supply J.

The segmented or mutilated inking roller E is secured on a shaft K rotated by handle L.—The segmented presser roller F is mounted on a spindle N rotated by its gear O 60 driven by the pinion M, and the said spindle N is carried in bearings formed in rocking arms P mounted on the cross bar Q secured in the frame R of the machine.

One of the arms P is extended and terminates in a fork S within which works a cam roller T fixed upon a spindle U which projects through the casing or frame R and has a handle or lever V fitted thereto. The uppermost surface, or top of the frame or 70 casing R is bored out to receive an adjustable pin or screw W the end of which acts upon the cam roller T, when the lever or handle V is turned in the rearward position as shown in Figs. 2 and 3. 75

The pinion O which rotates the mutilated presser roller F engages a pinion X mounted upon a spindle Y which by a usual crank and crank shaft arrangement operates the reciprocating pusher member D. The cam 80 roller T is provided with a pin or stop Z which limits the movement of the lever or handle V by contact against the adjustable screw W.

In the position of the parts shown in Figs. 85 2 and 3 the mutilated presser roller F and the inking roller E are in contact so that stencils B are acted upon, one at a time for printing when positioned by the reciprocating pusher member D between the said 90 rollers.

When, however, the operator observes that the reciprocating pusher member D has released a stencil for which an envelope, wrapper or label is not required, a movement of 95 the lever V in a clockwise direction, to the position shown in Fig. 1 releases the cam roller T from the adjustable screw W and the weight of the presser roller F causes its spindle N to depress the end of the rock 100 shaft P to an extent just sufficient to allow clearance between the segmented inking roller E and the presser roller F. This disconnection of the rollers E and F is not sufficient to prevent their respective pinions 105 M and O from meshing and consequently the timing of the rollers is not disturbed.

Through the disconnection of the surfaces of the roller the stencil card is pushed forward by the next stencil released by the 110

pusher member, and a counter clockwise movement of the lever V will permit the stencil following to be printed from.

The disconnection of the segmented rollers E and F is also advisable when the machine is not in use otherwise the ink from the inking roller will be imparted to the presser roller in the event of the machine being operated without stencils and envelopes.

Having thus described my invention, what I desire to secure by Letters Patent of the United States is as follows:

1. In an addressing or like printing machine of the type wherein stencils are automatically fed, from a supply of stencils, between a presser roller and an inking roller; means to rotate said rollers, pivotally mounted rocker arms upon which said presser roller is mounted, a manually operable lever and means operated thereby to actu-

ate said pivotally mounted rocker arms and move said presser roller out of contact with said inking roller whereby a printing operation may be selectively prevented upon a stencil as it passes between said printing and inking rollers.

2. In addressing or like printing machines the employment of means for discarding stencils comprising a mutilated presser roller mounted on a spindle carried in the ends of rocking arms, a fork formed in the extension of one of the arms, a cam roller rotatably fitted in said fork, an adjustable pin or screw acting upon said cam roller, and a lever for actuating the cam roller, and a pin upon said cam roller for limiting the turning movement of said lever.

In testimony I have signed my name to this specification.

LOUIS MAURICE BARMAN.
